UNITED STATES PATENT OFFICE

HARRY H. MCKEE AND GUSTAVE SCHULER, OF CHICAGO, ILLINOIS, ASSIGNEES TO SWIFT AND COMPANY, OF CHICAGO, ILLINOIS, A CORPORATION OF ILLINOIS.

BRANDING MACHINE

Application filed May 16, 1930. Serial No. 453,019.

This invention relates to a construction for applying identification marks on the edge of articles such as sides of bacon and is designed for automatic operation in that the articles to be branded are either manually or mechanically passed through the construction to receive the identification marks and such of the marking mechanism as is driven receives motion from the articles operated upon. The objects of the invention are to provide such a construction equipped with improved guiding means for the articles to be operated upon; improvements in the construction of a marking tool and means for applying ink thereto, and to provide a marking machine not requiring a driving means other than the traveling articles operated upon. The device herein shown and described is a specific development of the method and apparatus which are more broadly claimed in the co-pending applications of Harry H. McKee, Serial No. 208,668, filed July 27, 1927, for improvements in meat marking apparatus, and Serial No. 415,838, filed December 21, 1929, for improvements in method of marking meats.

In the drawings Figure 1 is a plan view of the marking table.

Fig. 2 shows the table in front elevation and partly in section taken on the line 2—2 of Figure 1.

Fig. 3 is a fragmentary sectional elevation taken on the line 3—3 of Fig. 1.

Fig. 4 is a detail in plan of the branding wheel and inking means therefor.

Fig. 5 is a side view of the branding wheel and inking means shown in Fig. 4.

The general arrangement of this branding construction is a table the top of which is divided to provide a longitudinal opening extending from end to end of the table. Below this opening is a series of horizontally disposed idling rollers for supporting edgewise articles which are branded as they pass through the machine.

Such articles are further supported by a series of vertically arranged rollers and an opposed presser roller. As the articles to be marked pass between this presser roller and the vertically disposed idlers, said articles

engage a branding wheel. The branding wheel is rotated because of this engagement and receives ink according to the extent to which it is rotated.

An ink feeding means is operated by the marking wheel. This wheel when used for branding the edge of the sides of bacon is for this purpose preferably provided with identification marking means such as needles arranged in the form of letters on the periphery of the wheel.

In the drawings a work table is shown in which the top is formed by two boards 1 and 2 separated to leave the intervening space 3. Between the boards 1 and 2, slightly below the surface thereof, is a series of horizontally disposed rollers 4, which may be trunnioned for pivotal mounting in the frame structure 5.

The marking wheel 6 at the end of the set of rollers 4 is also rotatable around a horizontal axis for which purpose it is mounted upon a fixed spindle 7 shown in Figure 5. The branding wheel is removable from the spindle and it is therefore provided with a handle 8. The wheel is normally retained on the spindle by the nut or collar 9 on the end of the spindle.

For the purpose of inking the branding wheel, an ink brush 10 is supported below the wheel in position to ink over needles 11 extending from the periphery of the wheel. The brush 10 is at the end of an ink conduit 12 leading from the ink reservoir 13 to the base of the brush.

A valve 14 regulates the rate at which the ink is allowed to flow from the reservoir to the brush. The handle 15 of this valve is connected by a rod 16 to an arm 17 which may oscillate around its pivotal support 18. At the end of arm 17 is a roller 19, which extends into the cam groove 20 cut into the face of a disk 21 secured to and therefore rotatable with the branding wheel. The extent to which the valve 14 is opened upon each rotation of the inking wheel may be varied by placing the bent end of rod 16 in different ones of holes 22 in arm 17. The ink reservoir may be filled at the opening 23 and drained by removing drain plug 24.

The marking wheel 6 is depressible with the inking unit which carries it by the action of articles operated upon. The inking unit is pivoted at 33 and is urged upwardly by 5 spring 34.

A row of vertically disposed idler rollers 25 assist in guiding sides of bacon and near the marking wheel 6 and opposite the rollers 25 is a pressure roller 26. This 10 roller may freely rotate upon the spindle 27 which is carried at the end of an arm 28 pivotally mounted on a fixed spindle 29 extending downwardly from the frame member 30. A spring 31 urges the presser 15 roller 26 toward the opposed vertically disposed idler rollers 25. Since the arm 28 which supports the presser roller 26 is located below the table top 2 and the roller is 20 above the table, the table top is provided with a curved slot 32 through which the spindle 27 extends.

In the operation of the branding table articles to be branded such as the sides of bacon are placed edgewise either manually or mechanically 25 on the rollers 4 and pushed forwardly as guided by the series of vertical rollers 25 and the resiliently mounted roller 26 between which and the rollers 25 the article is guided when receiving the incisions or 30 other marks from roller 6. This roller is driven by frictional engagement with the article operated upon, and the marking devices thereon, such as needles 11, are inked as they pass over brush 10. Ink is fed to the 35 brush from reservoir 13 as required, by the rocking of valve 14, the handle of which is connected through the links 16 and arm 17 with cam 21 rotatable with the marking wheel.

40 We claim:

1. In a branding construction a series of 45 horizontally disposed idler rollers for supporting articles which are pushed over the same, a series of vertically disposed guide rollers for guiding articles by engaging the sides thereof, a vertical resiliently mounted roller in position to engage the opposite sides of articles to be operated upon, a branding wheel mounted on a horizontal axis in position to engage the edge of an article passing between said rollers as it leaves the series of horizontally disposed supporting rollers.

2. In a branding construction a series of 55 horizontally disposed idler rollers for supporting articles which are pushed over the same, a series of vertically disposed guide rollers for guiding articles by engaging the sides thereof, a vertical resiliently mounted roller in position to engage the opposite sides 60 of articles to be operated upon, a branding wheel mounted on a horizontal axis in position to engage the edge of an article passing between said rollers as it leaves the series of horizontally disposed supporting rollers, 65 said rollers and said branding wheel being

arranged to be driven by the article operated upon, means for inking said branding wheel and means driven by said branding wheel for controlling the action of said inking means.

3. In a branding construction a series of 70 horizontally disposed idler rollers for supporting articles which are pushed over the same, a series of vertically disposed guide rollers for guiding articles by engaging the sides thereof, a vertical resiliently mounted 75 roller in position to engage the opposite sides of articles to be operated upon, a branding wheel mounted on a horizontal axis in position to engage the edge of an article passing between said rollers as it leaves the series of 80 horizontally disposed supporting rollers, means for inking the branding wheel comprising an ink applying means in position to engage the periphery of the branding wheel, an ink reservoir and ink feeding means, said 85 ink feeding means including a valve with connections for oscillating said valve, said connections being operable in unison with said branding wheel.

Signed at Chicago this 12th day of May 20 1930.

HARRY H. MCKEE.
GUSTAVE SCHULER.
